WORK HOLDER FOR PRESSING MACHINES

Fred A. Heidenfelder, Chicago, Ill., assignor to
The American Laundry Machinery Company,
Cincinnati, Ohio, a corporation of Ohio

Application July 12, 1930, Serial No. 467,491

9 Claims. (Cl. 68—9)

My invention relates to an attachment for pressing machines and, particularly, to an attachment commonly known as a tail clamp which is adapted to hold the tail of a shirt in such position on the buck of a press that it may be properly pressed while, at the same time, relieve the operator of the necessity of the use of the hands for holding the work in proper position thereon until the movable pressing member reaches such position relative to the pressing buck as to prevent any movement or distortion of the work.

Heretofore, there have been numerous types of tail clamps some of which embodied simply a flexible band secured on one side of the pressing buck and adapted to be drawn over the buck and any work thereon and secured on the other side of the buck to hold the work in position. Other types have embodied a swinging carrier frame adapted to be swung to such position as to place the clamping band crosswise of the buck and the work thereon or to such position as to remove the clamping band from the buck and work.

My invention contemplates the provision of a tail clamp embodying a flexible band mounted on a frame together with power operated mechanism and control means for swinging the carrier frame and clamping band to such position that the clamping band will be disposed cross-wise of the buck and over the work thereon, the same mechanism being adapted to move the carrier frame downwardly as a unit whereby the clamping band will be moved downwardly on the work with a direct vertical and no longitudinal movement of the band, and for moving the carrier frame and clamping band vertically upwardly and then swinging the frame and band to such position relative to the pressing buck that it will not interfere with the operator making the proper lay of work on the pressing buck.

Various other objects and advantageous features of my invention may be seen in the following description and one embodiment thereof may be seen in the accompanying drawing wherein similar characters of reference designate corresponding parts, and wherein:

Fig. 1 is an elevation, partly in section, showing a tail clamp constructed in accordance with my invention and the operating means therefor, the tail clamp being in operative position relative to the pressing buck; and Fig. 2 is an elevation of the tail clamp in operating mechanism shown in Fig. 1 showing the clamp out of operative relation with the pressing buck.

Referring to the drawing and particularly Fig. 1 thereof, I have diagrammatically shown part

of a pressing machine which may be of any well-known type and which consists of the usual pressing table 1 and pressing buck 2, all being suitably supported on a frame 3.

In accordance with my invention, I have provided a tail clamping device consisting of a flexible band 4 that is adapted to extend cross-wise of the buck 2 and hold any work to be pressed thereon, the flexible band 4 being supported by a carrier frame 5 disposed beneath the buck 2 when the clamping band 4 is in operative relation with the buck. Such clamping band is attached to the carrier frame 5 by means of suitable securing means 6.

The carrier frame 5 is mounted on the uppermost end of a shaft 7 rotatably and reciprocably mounted in a bracket 8 that may be secured to the frame of the pressing machine in any well-known manner and connected to a piston rod 7', the bracket 8 embodying an extension 9 which supports a cylinder 10 having a piston 11 therein and mounted on the piston rod 7', the piston 11 being operated by air pressure from a main line 12 through auxiliary lines 13 and 14 that respectively lead to the cylinder 10 above and below the piston 11. Flow of air pressure to the cylinder 10 is controlled by a valve 15.

As shown in the drawing, the bracket 8 embodies a portion 16 having a cam groove 17 therein that extends vertically for a portion of its length and then circumferentially around a part of the portion 16 of the bracket. A pin 18 having a roller 19 thereon extends outwardly from the shaft 7 and is adapted to follow the cam groove 17 and rotate the shaft a given distance either in one direction or the other during the reciprocation of the shaft 7 by following the circumferentially disposed part of the groove. This rotation will result in swinging of the carrier frame 5 and clamping band 4 into or out of operative relation with the buck 2.

In the operation of this device, it being assumed that the carrier frame and clamping band are in the position shown in Fig. 1 in which the clamping band 4 is in cooperative relation with the pressing buck 2, the valve 15 is operated in such manner that fluid pressure flows from the pipe 12, through the pipe 14 and to the under surface of the piston 11 to force the piston 11, piston rod 7', and shaft upwardly. The valve 15 is so arranged that the fluid pressure above the piston 11 will escape through the pipe 13 and valve 15 to the atmosphere. Upward movement of the piston 11 and connected parts, including the shaft 7, will move the carrier frame 5 and clamping band 4 into operative relation with the buck 2.

band 4 vertically upwardly off the buck and the work thereon so long as the pin and roller 18 and 19 follow the vertically extending portion of the cam groove 17. This movement serves to release 5 the work on the buck without any distortion thereof due to longitudinal movement of the clamping band 4. Then, when the pin and roller 18 and 19 strike the circumferentially disposed portion of the cam groove 17, the shaft 7 will be 10 rotated which will swing the carrier frame 5 that is rigidly attached thereto to the position in Fig. 2 wherein the carrier frame and clamping band are disposed at the rear of the buck and extend in the same general longitudinal direction. 15

The pressed work having been taken from the buck and another lay made thereon, the valve 15 is operated to permit fluid under pressure 20 to flow through the pipe 12, pipe 13 and to the upper surface of the piston 11 to move the piston downwardly. As in the previously described movement of the piston, the valve 15 is so arranged that fluid under pressure against the under side of the piston will then escape through 25 the pipe 14 and valve 15 to the atmosphere. At the beginning of the downward movement of the piston 11 and its connected parts hereinbefore described, the pin and roller 18 and 19 traveling in the circumferentially directed portion of the cam groove 17 will first swing the carrier frame 5 and clamping band 4 to the position shown in Fig. 1 wherein the carrier frame is below the buck and the clamping band above and cross-wise thereof. Continued downward movement of the piston 11 will bring the pin and roller 18 and 30 19 into the vertically extending position of the cam groove 17 whereby the clamping band 4 will be moved directly vertically downwardly onto the buck without any longitudinal movement 35 thereof, the parts being so arranged that the clamping band will have assumed its position cross-wise of the buck before the downward vertical movement begins and such downward movement will continue until the parts are in the position shown in Fig. 1 wherein the work will be 40 securely held on the buck by the clamping band 4.

Referring to the drawing and the preceding description, it will be seen that I have provided a device of the class described embodying numerous novel and advantageous features. For instance, I have provided a clamping band and carrier frame together with a power operated mechanism therefor of such nature that the clamping band may be swung cross-wise the buck by the 50 simple operation of a control element which may be in proximity with the other controls of the pressing machine and will be moved directly vertically downwardly without any longitudinal movement of the clamping band. This is highly important in that it will prevent any distortion 55 of the work by the clamping band moving into engagement therewith.

Another advantageous feature resides in the 60 fact that the carrier frame and clamping band may be swung either to a position wherein the clamping band will be crosswise of the buck or to such position as to extend in the same general longitudinal direction as the buck and be disposed to one side thereof and will move automatically downwardly onto the work or directly upwardly off of the work depending on the direction of operation of the valve. Various other 65 advantageous features will be readily apparent.

70 75 What I claim is:

1. In combination with a pressing machine including a support and a buck, a carrier frame, a clamping band mounted on said frame, and power operated means for swinging said clamping band over said buck and said carrier frame 5 under said buck and moving said clamping band into engagement with said buck or with work thereon, said power operated means embodying a cylinder and piston construction, a vertically extending reciprocable shaft on which said 10 clamping band is mounted, a stationary cam groove, and a pin and roller on said shaft and adapted to travel in said cam groove to swing said shaft and move said clamping band into 15 and out of operative position relative to said buck.

2. A work clamping unit for a pressing machine having a frame and a work supporting buck, said unit comprising a clamping band for holding work on said buck, a support for said band carried by said pressing machine frame and mounted on a vertical pivot, motor means 20 for swinging said band laterally into and out of working alignment with said buck and for moving said band vertically into and out of clamping engagement with said buck, and means for controlling the operation of the said motor means.

3. A work clamping unit for a pressing machine having a frame and a work supporting buck, said unit comprising a clamping band for holding work on said buck, a support for said band carried by said pressing machine frame and mounted on a vertical pivot disposed at the rear of said buck, motor means for swinging said band laterally into and out of working alignment with 30 said buck and for moving said band vertically into and out of clamping engagement with said buck, and means for controlling the operation of 35 said motor means.

4. A work clamping unit for a pressing machine having a frame and a work supporting buck, said unit comprising a clamping band for holding work on said buck, a support for said band carried by said pressing machine frame and mounted on a vertical pivot disposed at the 40 rear of said buck, motor means for swinging said band laterally from an inoperative position substantially parallel with the longitudinal axis of said buck into and out of working alignment with said buck and for moving said band in a direct 45 vertical line into and out of clamping engagement with said buck, and means for controlling the operation of said motor means.

5. In combination with a pressing machine including a supporting frame and a buck, a clamping band for holding work on said buck, a pivotally mounted support for said band, and power operated means for swinging said clamping band into and out of working alignment with said buck and into and out of clamping engagement therewith, said power operated means embodying a cylinder and piston construction, a vertically extending reciprocable shaft on which said clamping band is mounted, a stationary cam groove in 55 said cylinder having a portion arranged at an acute angle to the axis of the shaft and another portion parallel to the shaft, and a pin and roller on said shaft and adapted to travel in said cam groove to swing said shaft and move said clamping band into and out of working alignment with 60 said buck and into and out of clamping engagement therewith.

6. A pressing machine including in combination elongated upper and lower pressing elements 65 having relative movement one toward and from 70 said buck and into and out of clamping engagement therewith.

75

the other; a work grip cooperating with the lower pressing element; means supporting the work grip for movement toward and away from one end of the lower pressing element, in the direction of the length of the lower pressing element, into and out of position over the margin of the pressing face of said element, and a power means for moving the work grip into such position, and for moving said work grip rectilinearly toward said lower pressing element; and for moving the work grip in a reverse manner out of operative position.

7. In a pressing machine, a work supporting member, a work grip for cooperation with said work supporting member, a bracket, a carriage for said work grip mounted in said bracket for pivotal and slidable movement, the pivotal movement of said carriage effecting movement of said work grip back and forth between an out-of-the-way position and a position overlying said work supporting member and the slidable movement of said carriage effecting movement of said work grip back and forth between said overlying position and a position in clamping engagement with said work supporting member, and means for actuating said carriage to effect such pivotal and slidable movement of the work grip carried thereby.

8. In a pressing machine, a work supporting member, a work grip for cooperation with said work supporting member, a bracket, a carriage

for said work grip mounted in said bracket for pivotal and slidable movement, the pivotal movement of said carriage effecting movement of said work grip back and forth between an out-of-the-way position and a position overlying said work supporting member and the slidable movement of said carriage effecting movement of said work grip back and forth between said overlying position and a position in clamping engagement with said work supporting member, means for actuating said carriage to effect such pivotal and slidable movement of the work grip carried thereby, and means for limiting the pivotal movement of said carriage when said work grip has reached said overlying position after movement from said out-of-the-way position.

9. In a pressing machine, a work supporting member, a work grip for cooperation with said work supporting member, means for supporting the work grip for movement over the end of said work supporting member into and out of position over the margin of the work supporting face of said member and for movement vertically toward and from said member, and means for actuating the work grip to successively move the same from said margin of said work supporting member and then move the work grip rectilinearly toward the work supporting member to grip work thereon and for moving said work grip out of operative position in reverse order.
